UNITED STATES PATENT OFFICE.

ARTHUR LINDENMAYER, OF LANSDOWNE, PENNSYLVANIA.

RECEPTACLE FOR HOLDING POWDERED MATERIAL OR THE LIKE.

Application filed January 23, 1923. Serial No. 614,424.

To all whom it may concern:

Be it known that I, ARTHUR LINDENMAYER, a citizen of the United States, residing at Lansdowne, in the county of Delaware and State of Pennsylvania, have invented certain new and useful Improvements in Receptacles for Holding Powdered Material or the like, of which the following is a specification.

10 My invention relates to improvements in receptacles for holding powdered or finely divided material, while not necessarily restricted to this use.

An important object of the invention is 15 to provide a receptacle of the above mentioned character, having means whereby the air may be effectually excluded from the presence of the contents of the receptacle, when the receptacle is in an upright position, and such contents may be freely discharged or sprinkled from the receptacle, when it is inverted.

A further object of the invention is to 20 provide a device of the above mentioned character, which is of simple construction and is inexpensive to manufacture.

Other objects and advantages of the invention will be apparent during the course 25 of the following description.

30 In the accompanying drawings forming a part of this specification, and in which like numerals are employed to designate like parts throughout the same,

Figure 1 is a central vertical sectional 35 view through a receptacle embodying my invention, showing the same in an upright position,

Figure 2 is a similar view through the 40 receptacle, showing it inverted,

Figure 3 is a central vertical sectional 45 view through a modified form of the invention,

Figure 4 is a horizontal section taken on line 4—4 of Figure 3, and,

Figure 5 is a fragmentary central vertical 50 longitudinal section through a third form of receptacle embodying my invention.

Attention being called first to Figures 1 and 2 the numeral 10 designates a receptacle, of any well known or preferred construction. The upper portion of this receptacle is contracted to provide a shoulder 11, terminating in a neck 12. This neck is covered by a plate 13, preferably formed 55 integral therewith. This horizontal plate is

provided adjacent to the neck 12 with an annular groove 14, which is transversely curved. This annular groove or depression has its material in its bottom provided with an annular set of apertures 15.

60 The numeral 16 designates a neck-sleeve or neck-element having its lower end open, and fitted upon the neck 12, and secured thereto by any suitable means. The neck-sleeve or neck-element 16 preferably forms an air tight joint with the neck 12. The upper end of the neck-sleeve or neck-element 16 is covered by an outer plate 17, which is provided adjacent to the sleeve 16 with an annular set of apertures 18.

65 The numeral 19 designates a tubular guiding element, which is circular in cross-section. This tubular guiding element is curved in longitudinal section, providing flaring ends 20 and 21. The tubular guiding element 19 is rigidly secured to the lower plate 15 by any suitable means, and the lower end of this tubular guiding element is closed 70 by this plate 15. The diameter of the lower end of the tubular guiding element 19 is such that its outer surface leads into the inner side of the annular groove or depression 14, while the diameter of the upper end of this guiding element is larger than that of its lower end, and its upper end projects radially beyond the lower end, and terminates adjacent to the apertures 18, but does not 75 cover them.

80 The numeral 22 designates a ring-valve, which is mounted in the neck-sleeve or neck-element 16, and surrounds the guiding element 19. This ring-valve is of a proper diameter to fit snugly within the annular groove 14, and hence completely cover the apertures 15. The ring-valve is guided to 85 the lowermost position, by contact with the lower flaring end 20 of the guiding element. When the receptacle is inverted, as shown in Figure 2, the larger flaring end 21, retains the ring-valve 22 spaced from the outer plate 17, and hence this ring-valve cannot 90 cover the outer apertures 18. It is thus seen that the powdered material, such as talcum powder, salt, or the like, may freely shake through the apertures 15 and 18.

95 In Figures 3 and 4, I have shown a second form or modification of the invention. In these figures the numeral 23 designates a receptacle having a contracted shoulder 24, upon which a plate 25 is suitably mounted.

This plate is provided near its marginal edge with an annular depression or groove 26, having apertures 27, arranged in an annular set. The numeral 28 designates a neck-sleeve or neck-element, which is suitably attached to the plate 25, exteriorly of the groove 26, and this neck-sleeve or neck-element has its top covered by a plate 29, having apertures 30.

- 10 The numeral 31 designates a ring-valve adapted to sit snugly within the annular groove 26 to cover the apertures 27. This ring-valve is guided by slidable contact with the inner side of the neck-sleeve or neck-element 28, and its outward movement is limited by means of a spider 32, secured within the neck-sleeve or neck-element, as shown. This spider retains the ring-valve spaced from the apertures 30.
- 20 In this construction, it is obvious that I have provided a device wherein the contents of the receptacle are effectually excluded from air or dampness, while the contents may be readily discharged through the apertures 27 and 30, and be sprinkled thereby.

In Figure 5 I have illustrated a third modification of the invention. In this figure the numeral 33 designates a receptacle, 30 having a neck or neck-element 34 formed integral therewith. The top of the neck-element may be covered by a perforated plate 35, suitably secured thereto. The numeral 36 designates an inner plate, anchored in the neck element 34, near its inner end. The inner plate 36 has an annular set of apertures 37, through which the powdered material may pass. Two of these apertures slidably receive rods 38, attached to a ring-valve 39, which is adapted to cover the apertures 37, and to be seated within the annular groove or depression in which these apertures are formed. The inner ends of the rods 38 carry heads 40, to limit the outward movement of the ring-valve 39.

In view of the foregoing description it is obvious that the ring-valve 39 will permit of the free discharge of the material 50 through the sets of apertures in the inner and outer plates, and that when the receptacle is in the upright position, it will cover the apertures 37, and exclude the air and moisture from the interior of the receptacle.

55 It is to be understood that the forms of my invention herewith shown and described are to be taken as preferred examples of the same, and that various changes in the shape, size, and arrangement of parts may be resorted to without departing from the spirit of my invention or the scope of the subjoined claims.

Having thus described my invention, I claim:

- 65 1. A receptacle comprising a body por-

tion, a neck-element carried by the body portion and having its outer end covered by an apertured plate, an inner plate mounted in the inner end of the neck-element and having an annular depression 70 which is provided with an annular set of apertures, and a ring-valve mounted within the neck-element and adapted to enter the annular depression.

2. A receptacle comprising a body portion, a neck-element carried by the body portion and having its outer end covered by an apertured plate, an inner plate disposed near the inner end of the neck element and having an annular set of apertures, and a ring-valve mounted within the neck-element and adapted to cover and uncover the set of annular apertures.

3. A receptacle comprising a body portion, a neck-element carried by the body portion and having its outer end covered by an apertured plate, an inner plate disposed near the inner end of the neck-element and having an annular set of apertures, a ring-valve mounted within the neck-element and adapted to cover and uncover the annular set of apertures, and means to limit the outward movement of the ring-valve toward the outer apertured plate.

4. A receptacle comprising a body portion, there being an annular set of apertures near the upper end of said body portion, a neck-element carried by the body portion and having its outer end covered by an apertured plate, a ring-valve mounted within the neck-element to cover and uncover the annular set of apertures, and means to limit the outward movement of the ring-valve toward the outer apertured plate.

5. A receptacle comprising a body portion, there being an annular set of apertures near the upper end of said body portion, a neck-element carried by the body portion and having its outer end covered by an apertured plate, a ring-valve mounted within the neck-element, guide means for the ring-valve to seat the same upon the annular set of apertures, said guide means serving to limit the outward movement of the ring-valve toward the outer apertured plate.

6. A receptacle comprising a body portion with an annular set of apertures arranged near the upper end of said body portion, a ring-valve to cover and uncover the annular set of apertures, and guide means for the ring-valve to seat the same upon the annular set of apertures.

7. A receptacle comprising a body portion with an annular set of apertures arranged near the upper end of the body portion, a neck-element carried by the body portion and surrounding the annular set of apertures, a guiding element mounted upon the body portion within the annular set of apertures and having outwardly flaring in-

ner and outer end portions, a ring-valve within the neck and surrounding the guiding element, and a plate carried by the outer end of the neck-element and having an annular set of apertures disposed outwardly of the marginal edge of the outer flaring end of the guiding element.

8. A receptacle comprising a body portion with an annular set of apertures arranged near the upper end of said body portion, a neck-element carried by the body portion and surrounding the annular set of apertures, a guiding element mounted

upon the body portion within the annular set of apertures and having outwardly flaring inner and outer end portions, the outer flaring end portion having the larger diameter, a ring-valve within the neck-element and surrounding the guiding element, and a plate carried by the outer end of the neck-element and having an annular set of apertures disposed outwardly of the marginal edge of the outer flaring end of the guiding element.

In testimony whereof I affix my signature. 25
ARTHUR LINDENMAYER.
